UNITED STATES PATENT OFFICE.

CHARLES B. OTT, OF ECHO POINT, WEST VIRGINIA.

DESIGN FOR AN ARTIFICIAL-LIGHT INCLOSURE.

46,061.

Specification for Design.

Patented July 7, 1914.

Application filed May 8, 1914. Serial No. 837,346. Term of patent 3½ years.

To all whom it may concern:

Be it known that I, CHARLES B. OTT, a citizen of the United States, residing at Echo Point, in the county of Ohio and State of West Virginia, have invented a new, original, and ornamental Design for Artificial-Light Inclosures, of which the following is a specification, reference being had to the accompanying drawing, forming part thereof.

Figure 1 is a bottom plan view of an arti-

ficial light inclosure, showing my new design; and Fig. 2 is a side elevation of the same.

I claim:

The ornamental design for an artificial light inclosure, as shown.

CHARLES B. OTT.
